UNITED STATES PATENT OFFICE.

ELMER J. WELLS, OF NASHUA, IOWA.

FENCE-POST.

1,174,457.

Specification of Letters Patent.

Patented Mar. 7, 1916.

Application filed April 13, 1915. Serial No. 21,090.

To all whom it may concern:

Be it known that I, ELMER J. WELLS, a citizen of the United States, residing at Nashua, in the county of Chickasaw and State of Iowa, have invented a new and useful Fence-Post, of which the following is a specification.

The device forming the subject matter of this application is a fence construction and the invention aims to provide a novel form 10 of wire fastening means.

With the above and other objects in view which will appear as the description proceeds, the invention resides in the combination 15 and arrangement of parts and in the details of construction hereinafter described and claimed, it being understood that changes in the precise embodiment of the invention herein disclosed can be made without 20 in the scope of what is claimed, without departing from the spirit of the invention.

In the accompanying drawings:—Figure 1 shows the invention in front elevation; Fig. 2 is a top plan of a post embodying the 25 present invention, parts being omitted; Fig. 3 is a fragmental rear elevation of post embodying the present invention; Fig. 4 is an elevation of the post wherein the latter appears at right angles to the showing of 30 Fig. 1.

In carrying out the present invention there is provided a post 1 which is fashioned from metal. The line post 1 may be of any desired contour without jeopardizing the 35 utility of the fence fastening means, but in the present instance, the post has been shown in the form of a channel member comprising a body 2 and side flanges 3 and 4. In the body 2 of the line posts 1, keyhole slots 40 5 are formed, the reduced extensions of which are denoted by the reference character 6. In the formation of the keyhole slots 5 outwardly extended, downwardly slanting tongues 7 are fashioned. The tongues 7 are 45 provided with openings 8 having functions which will be set forth hereinafter. In the body portion 2 of the line post 1 near to the top thereof is formed an opening 9. In the side flanges 3 and 4 of the line post near 50 to the top thereof are formed openings 10.

The fence which is sustained by the posts 1 may be of various forms. When the fence comprises, as shown, longitudinal wires 30, these wires are engaged beneath the inclined 55 tongues 7 and are lodged in the angles defined by the tongues and the body 2. The

longitudinal wires 30 of the fence are held in place by means of removable securing elements 31 which may be wire nails, the securing elements being passed through the 60 openings 8 in the tongues 7 and being lodged in the recessed extensions 6 of the keyhole slots 5.

The securing means may take the form of a wire 33, passing through a lower opening 65 32 in the body 2 of the post 1, the lower end of the wire 33 being knotted or twisted against the rear face of the body 2 of the line post 1 as indicated at 34 in dotted line in Fig. 4. The wire is then extended upwardly in sinuous form and engages opposed edges of the tongue 7, the wire passing inside of the securing elements or nails 30. The upper end of the wire 33 is passed through the opening 9 in the body 2 of the 70 line post 1 and then is engaged through the 75 openings 10 formed in the flanges 3 and 4 of the line post.

The wire 33 has been shown as used in combination with the nails or securing elements 31, but those skilled in the art will understand that either of the wire holding means above alluded to may be used to the exclusion of the other, depending upon the 80 character of the fence which is assembled 85 with the post 1.

It is to be observed that the tongues 7 do not standout at right angles to the body 2 of the line post 1. Owing to this construction, the strength of the tongues 7 is increased and the hold thereof on the fence 90 wires is enhanced.

Having thus described the invention, what is claimed is:

1. In a device of the class described, a 95 post having a plurality of tongues struck therefrom; a wire extended in sinuous form longitudinally of the post, the wire engaging opposed edges of the respective tongues, the tongues overhanging portions of the wire and being inclined with respect to the outer face of the post; and means for securing the ends of the wire.

2. In a device of the class described, a 100 post having tongues struck therefrom to define openings, the openings being elongated beyond the tongues to form slotted extensions; and removable securing elements passing through the tongues and engaged in the extensions.

3. In a device of the class described, a 105 post having tongues struck therefrom and

defining part of a keyhole slot in the post, the slot comprising a reduced extension; and a securing element passing through the tongue, one end of the securing element being lodged in the reduced extension of the keyhole slot.

4. In a device of the class described, a post having a plurality of tongues struck therefrom and a wire extended in sinuous form longitudinally of the post, the wire engaging opposed edges of the respective tongues and the ends of the wire being connected to the post; the tongues overhanging portions of the wire and being inclined with respect to the outer face of the post.
5. In a device of the class described, a

post having fence holding tongues struck therefrom and defining openings in the post; securing elements extended through the tongues and lodged in the openings; and a fence securing wire extended in sinuous form longitudinally of the post, the wire engaging the opposed edges of the respective tongues and passing between the securing elements and the bases of the tongues. ²⁰

In testimony that I claim the foregoing as my own, I have hereto affixed my signature in the presence of two witnesses.

ELMER J. WELLS.
